UNITED STATES PATENT OFFICE

91,690

DESIGN FOR AN EMBLEMATIC PIN OR SIMILAR ARTICLE

Mary W. F. Speers, Washington, D. C.

Application December 22, 1933, Serial No. 50,193

Term of patent 3½ years

To all whom it may concern:

Be it known that I, MARY W. F. SPEERS, a citizen of the United States, residing at Washington, District of Columbia, have invented a new, original, and ornamental Design for an Emblematic Pin or Similar Article, of which the following is the specification, reference being had to accompanying drawing forming part hereof.

In the drawing:

Fig. 1 represents a front view of the pin showing my new design; and

Fig. 2 represents an edge view of the pin.

It is understood that my design may be embodied in such articles as pins, buttons, badges, signs, pennants or placards, without departing from the spirit of my invention.

I claim:

The ornamental design for an emblematic pin or similar article, as shown and described.

In testimony whereof, I affix my signature.

MARY W. F. SPEERS.
